Specification for Design.

Patented Dec. 15, 1914.

Application filed October 23, 1914. Serial No. 868,342. Term of patent 7 years.

To all whom it may concern:

Be it known that I, FRANK W. TRABOLD, a citizen of the United States of America, residing in the borough of Brooklyn, county of Kings, State of New York, have invented a new, original, and ornamental Design for an Automobile Tire-Tool, of which the following is a specification, reference being had to the accompanying drawing, forming part thereof.

Figure 1 is a side view of my new design. Fig. 2 is a front view; and Fig. 3 is a reverse view thereof.

Copies of this patent may be obtained for five cents each, by addressing the "Commissioner of Patents, Washington, D. C."

I claim:

The ornamental design for an automobile tire tool as shown.

In witness whereof, I have hereunto signed my name in the presence of two subscribing witnesses.

FRANK W. TRABOLD.
